(57) **CLAIM**

The ornamental design for a photographic camera, as shown and described.

DESCRIPTION

1.-2. Photographic camera

1.1 is a perspective view of a photographic camera showing our new design;

1.2 is a bottom view thereof;

1.3 is a rear view thereof;

1.4 is a left elevational view thereof;

1.5 is a right side elevational view thereof;

1.6 is a top view thereof; and

1.7 is a front view thereof.

2.1 is a perspective view of a photographic camera showing a second embodiment of our design;

2.2 is a bottom view thereof;

2.3 is a rear view thereof;

2.4 is a left elevational view thereof;

2.5 is a right side elevational view thereof;

2.6 is a top view thereof; and

2.7 is a front view thereof.

The broken lines in the figures form no part of the claimed design.
